WINDOW SHUTTER

Lee W. Kolterman, North Kansas City, Mo., assignor to Frederick W. Bopp and Edward Otto Bopp, both of Kansas City, Mo.

Application October 13, 1948, Serial No. 54,219

1 Claim. (Cl. 160—176)

1

This structure relates to new and useful improvements in window shutters or blinds, and is an improvement over the window shutter covered by co-pending application Serial No. 18,186, filed March 31, 1948, which issued October 3, 1950, as Patent No. 2,524,372, in which I am co-applicant.

The principal object of the present invention is the provision of a window shutter having a plurality of parallel, vertically disposed flexible slats, and improved and simplified means whereby said slats may be rotated about their respective longitudinal axes to control the passage of light and air therethrough.

Another object is the provision of means whereby said flexible slats may be adjustably twisted about their respective longitudinal axes, whereby said shutter may be simultaneously closed at one end and open at the other. This permits better light control by the shutter, and presents novel decorative effects.

Other objects are simplicity and economy of construction, ease and convenience of operation, and adaptability for use wherever a shutter for controlling light and air is needed.

With these objects in view, as well as other objects which will appear in the course of the specification, reference will be had to the drawing, wherein:

Figure 1 is a front elevational view of a window shutter embodying the present invention, mounted on the inside of a window frame.

Fig. 2 is a sectional view taken on line II—II of Fig. 1.

Fig. 3 is a sectional view taken on line III—III of Fig. 1.

Fig. 4 is an enlarged and foreshortened sectional view taken on line IV—IV of Fig. 1.

Fig. 5 is an enlarged and foreshortened plan view of the shutter.

Fig. 6 is an enlarged fragmentary section taken on line VI—VI of Fig. 5.

Fig. 7 is an enlarged fragmentary section taken on line VII—VII of Fig. 5.

Fig. 8 is a fragmentary section taken on line VIII—VIII of Fig. 6.

Fig. 9 is a fragmentary section taken on line IX—IX of Fig. 7.

Fig. 10 is an enlarged section taken on line X—X of Fig. 4.

Fig. 11 is an enlarged fragmentary section taken on line XI—XI of Fig. 5.

Like reference numerals apply to similar parts throughout the several views and the numeral 2 applies to a window frame of the usual type. A pair of mounting brackets 4 are mounted respec-

tively at opposite sides of said window frame on the inner face thereof and adjacent the upper and lower ends thereof. Each of said brackets comprises a vertically disposed rectangular sheet of metal having a flange 6 at its rearward edge adapted to be secured to window frame 2 by any suitable means such as screws 8. A front panel 10 extends horizontally across window frame 2 between the outer ends of said upper and lower pairs of mounting brackets, and are attached to said mounting brackets by corner fixtures 12. Said corner fixtures each comprise a sheet of metal having a portion 14 disposed adjacent the outer surface of the associated mounting bracket, the upper and lower edge portions of portion 14 being rebent inwardly to form channels 16 adapted to engage slidably the upper and lower edges of bracket 4, and a portion 18 disposed adjacent the outer surface of front panel 10 and having its upper and lower edge portions rebent inwardly to form channels 20 for engaging the upper and lower edges of front panel 10. Thus said front panels may be easily removed at any time by pulling outwardly thereon to disengage fixtures 12 from mounting brackets 4. An inwardly opening, horizontally disposed channel 22 is welded or otherwise rigidly fixed to the inner surface of each mounting bracket 4.

Referring principally to the structure at the top of the window, as shown in Figs. 4 to 9, it will be seen that a horizontally disposed, substantially planar support bar 24 extends between mounting brackets 4, the end portions thereof being slidably disposed in channels 22. Said support bar may be disengaged from said channels by sliding it forwardly after front panel 10 has been removed. A longitudinal groove 26 is formed in the upper surface of support bar 24 and extends the entire length thereof. A metallic bearing plate 28 substantially coextensive with groove 26 is fixed to the support bar within said groove by screws 30. A series of vertically disposed, horizontally spaced apart shafts 32 are carried for rotational and longitudinal movement by said bearing plate. All of said shafts are identical, and may be economically stamped from sheet metal or other suitable material. As best shown in Fig. 6, each shaft comprises an axial portion 34, a horizontal transverse arm 36 disposed beneath support bar 24, and a connecting portion 38. Axial portion 34 of the shaft is rectangular in cross section, and passes rotatably through a round hole 40 formed therefor in support bar 24. Said shaft is reduced in width adjacent the upper surface of said support bar, and extends rotatably through a round

hole 42 formed therefor in bearing plate 28. The shoulders 44 formed on the shaft by reducing the width thereof are adapted to contact the lower surface of the bearing plate to limit the upward movement of the shaft.

A flat pinion 46 is carried slidably on the upwardly extended end of each shaft 32. All of said pinions except one is provided with a central rectangular hole 48 through which said shaft extends, thereby preventing rotation of said pinion on said shaft. One of said pinions, further designated by the numeral 50 and disposed at the right end of the shutter as viewed in Fig. 5, is provided with an enlarged central hole 52. A polygonal tube 54 is disposed beneath support bar 24, being adjacent and parallel to shaft 32 associated with pinion 50, said tube is provided with an upwardly projecting non-circular extension 56 which projects upwardly through support bar 24 and through hole 52 of pinion 50, said hole being so shaped as to prevent relative rotation of shaft 32 and extension 56. A helical compression spring 60 is disposed about the upwardly extended portion of each shaft 32, bearing at its lower end against pinion 46 and at its upper end against a pin 62 inserted transversely through said shaft adjacent its upper end. Spring 60 associated with pinion 50 also encircles tube extension 56, and pin 60 passes through said extension as shown in Fig. 7, thereby securing said tube member in position. Springs 60 serve to urge shafts 32 upwardly, and to retain pinions 46 against bearing plate 28 regardless of the position of said shafts. An elongated rack 64 is secured slidably to the upper surface of bearing plate 28 by means of screws 66, which extend through elongated slots 68 formed longitudinally in said rack. Said rack extends longitudinally of plate 28, and meshes with all of pinions 46 carried by said plate.

As shown in Figs. 3 and 4, support bar 24 and the structure carried thereby at the bottom of the window is substantially identical with that at the top of the window, except that it is inverted. A plurality of flexible slats or strips 70 are disposed in parallel relation between the upper and lower series of shafts 32. Said strips may be made of fabric or other suitable material, and each strip is looped at each end as at 72 to engage the transverse arms 36 of corresponding shafts 32 at the top and bottom of the window. Said strips are tensioned by springs 60 and are sufficiently wide to overlap slightly when they are moved to substantially coplanar relation, as shown in Fig. 1 and in dotted lines in Fig. 2.

Strips 70 may be turned each about its longitudinal axis by means of a vertical rod 74 having its end portions disposed slidably respectively in tubes 54 at the top and bottom of the window, as best shown in Fig. 4. Said rod is polygonal in cross-section, and said tubes are correspondingly shaped, as shown in Fig. 10, thereby preventing rotation of said rod in said tubes. Said rod is supported by means of a collar 76 clamped thereon by set screw 78 and adapted to rest on the upper end of lower tube 54. Rod 74 may be manually oscillated by means of a handle 80 carried on said rod intermediate its ends. Said handle may be pivoted to said rod at 82 so as to lie against said shaft when not in use, as shown in solid lines in Fig. 1, and may be extended as shown in dotted lines whenever it is desired to adjust the shutter.

Thus when rod 74 is turned, tubes 54 and pinions 50 associated therewith will be turned,

and pinions 50 will drive rack 64 to turn pinions 48, thereby turning all of shafts 32 simultaneously in the same direction. Strips 70 carried by said shafts may thereby be continuously adjusted from a closed, substantially coplanar position as shown in Figs. 1 and 2, to a full open position as shown in dotted lines in Fig. 2, wherein the strips are substantially normal to the plane of the window, thereby regulating the light and air passages between the strips. The strips may be oscillated through substantially 180 degrees, thus exposing either side of said strips to the room. This offers decorative possibilities, since the strips may have opposite sides of contrasting colors, or carry different designs, etc.

By lifting rod 74 to disengage it from lower tube 54, either the upper or lower ends of the strips may be turned while leaving the opposite ends stationary. This causes each of strips 70 to be twisted about its longitudinal axis. When the desired degree of twist has been obtained, rod 74 is reinserted in sleeve 54. In the drawing, rod 74 is shown hexagonal, thus permitting six different angular relationships between the upper and lower ends of the strips.

However, it is apparent that a rod having any regular polygonal cross-section could be used, thereby procuring adjustment in any increments desired. Since the shutter in this manner may be closed at the bottom and open at the top, or vice versa, a greater degree of control of the light passing therethrough is obtained. Furthermore, this arrangement offers a wide variety of decorative opportunities. The twisted slats are pleasing in appearance, and a novel effect is obtained by the long, narrow triangular light openings alternated with strips of various colors. Furthermore, by this adjustment both sides of the strips may be exposed simultaneously, and if said sides are of contrasting colors, an artistic appearance is achieved.

While a specific embodiment of my invention has been disclosed it is apparent that many minor changes of construction and operation could be made without departing from the spirit of the invention.

What I claim is:

A window shutter comprising a pair of vertically spaced apart support members adapted to be attached respectively adjacent the upper and lower edges of a window frame, like series of vertically disposed shafts carried by each of said support members for oscillatory and longitudinal movement, flexible strips each connected at its opposite ends to corresponding shafts of said two series of shafts, a geared pinion carried for longitudinal movement on the extended outer end of each of said shafts but restrained from rotation relative thereto, resilient means whereby said upper and lower series of shafts are urged apart to tension said strips and whereby the pinions carried by each support member are held in coplanar relation against said support member regardless of the longitudinal movement of said shafts, a rack carried slidably by each of said support members and meshing with each of the pinions carried thereby, a polygonal tubular member secured to one of said shafts and disposed parallel thereto, a like tubular member secured to the corresponding shaft in the other of said series of shafts, a polygonal rod having its end portions slidably disposed in said tubular members, said rod being disengageable from one of said tubular members whereby the tubular

members may be oscillated independently, and
manual means for oscillating said rod.

LEE W. KOLTERMAN.
